W. J. MORTON.
 WORK HOLDER FOR LETTER SHEET PERFORATING MACHINES.
 APPLICATION FILED MAR. 29, 1916.
1,265,696. Patented May 7, 1918.

Inventor
 William J. Morton
 by *J.W. Gammie, Atty*

UNITED STATES PATENT OFFICE.

WILLIAM J. MORTON, OF NEW YORK, N. Y., ASSIGNOR TO MCBEE BINDER COMPANY, OF ATHENS, OHIO, A CORPORATION OF OHIO.

WORK-HOLDER FOR LETTER-SHEET-PERFORATING MACHINES.

1,265,696.

Specification of Letters Patent. Patented May 7, 1918.

Original application filed June 30, 1914, Serial No. 848,187. Divided and this application filed March 29, 1916, Serial No. 37,481.

To all whom it may concern:

Be it known that I, WILLIAM J. MORTON, a citizen of the United States, residing at New York city, New York, have invented a certain new and useful Improvement in Work-Holders for Letter-Sheet-Perforating Machines, of which the following is a full, clear, and exact description, such as will enable others skilled in the art to which it appertains to make and use the same, reference being had to the accompanying drawings, forming part of this specification.

My invention relates generally to new and useful improvements in machines utilized for perforating and binding paper or other sheets, such for instance, as way-bills, checks and the like, and more particularly to a holder or container for that portion of the pile of sheets through which the perforations are formed.

This application is a division of an application filed by me June 30, 1914, Serial Number 848,187, for perforating and binding machines for letter sheets.

The principal objects of my invention are, to generally simplify and improve upon the existing machines of the type to which my invention relates, and further, to combine with the type of perforating and binding machine disclosed in my copending application just referred to, a simple work holder in the form of a container or assembling box for the sheets to be perforated, a portion of which holder is hinged so that it may be readily swung downward into an out of the way position, while the sheets after being perforated are being engaged by parts of a temporary or permanent binder.

A further object of my invention is to provide a machine of the character specified which is comparatively simple in construction and operation, inexpensive in manufacture, effective and reliable in use, and possessing the capacity for effecting a material saving of time and labor in the operations incident to the perforating and binding of letter sheets or the like.

With the foregoing and other objects in view, my invention consists in certain novel features of construction and arrangement of parts, hereinafter more fully described,

claimed and illustrated in the accompanying drawings, in which—

Figure 1 is a side elevational view of a perforating and binding machine which is equipped with a work holder of my improved construction, said work holder being shown in section.

Fig. 2 is a plan view of the central portion of my improved work holder and showing a portion of the table of the perforating and binding machine with which said work holder is associated.

Fig. 3 is a front elevational view of a perforating and binding machine, the same being equipped with my improved work holder.

Fig. 4 is a detail section taken approximately on the line 4—4 of Fig. 1.

Referring by numerals to the accompanying drawings, 10 designates the base of a perforating and binding machine, which base is preferably in the form of a table, and projecting forwardly from the front corners of said table are extensions 11 which serve as supports for upright frames 12. Hinged to the front edge of the table between the extensions 11, is a plate 13 which, when in horizontal position, occupies the same plane with the table 10. Formed integral with or fixed to the front edge of this plate 13 is a vertical plate or wall 14 and thus said plates 13 and 14 form a member which is substantially L-shape in cross section and serves as the front wall and forward portion of the assembling box or sheet container. Formed through the plate 13 is a series of apertures 15 which are adapted to accommodate the drills 16 which are utilized for forming the perforations through the letter sheets, said drills being carried by the lower ends of vertically moving rotatably mounted spindles 17.

Pivotaly mounted on the underside of the table 10 to the rear of the central portion of the plate 13 is the rear end of a horizontally disposed lever 18, the same carrying at its forward end a depending handle 19. Formed on the top of this lever is a rib or lug 20 which is adapted to engage beneath a rib 21, the same being formed on the underside of plate 13. Formed in the top of

table 10, a short distance from the front edge thereof, is a longitudinally extending groove 22, the same being parallel with the front edge of said table and substantially of inverted T-shape in cross section. Arranged to slide in this groove are the heads of upwardly projecting screws 23 which carry vertically disposed side plates 24, and located on the threaded ends of said screws 10 are winged nuts 25 which when tightened maintain the plates 24 in their adjusted positions. These plates form the sides of the assembling box or container and by loosening the winged nuts 25, said plates may be 15 readily adjusted toward or away from each other as may be required for sheets of differing widths. The means utilized for clamping the letter sheets in the holder or assembling box comprises a clamping bar 20 27 the ends of which are arranged to slide upon vertically disposed ribs 28 formed on the inner faces of uprights 12, and said bar being raised and lowered by means of slotted segmental plates 29, which latter are 25 mounted upon and actuated by a sheet 30. This clamping bar and its operating mechanism forms no part of the present invention, but is described and claimed in a co-pending application filed March 29, 1916, 30 Serial No. 87,482.

To arrange the holder or assembling box for use, the L-shaped member comprising parts 13 and 14 is swung upward into the position illustrated by solid lines in Fig. 1 35 and lever 18 is swung around into a transverse position beneath said L-shaped member with the lug 20 bearing against the underside of rib 21, thus holding said L-shaped member in normal position. The upright 40 plates 24 are now adjusted toward or away from each other to correspond to the width of the sheets to be perforated, and after proper adjustment these plates are secured in position by tightening the winged nuts 45 25. The sheets are now piled on the table 10 and on the plate 13 with their front edges against the vertical plate 14 and their side edges against plates 24. When the pile 50 of sheets has been completed and it is desired to perforate the same in order that they may be placed in a temporary or permanent binder, the clamping bar 27 is moved downward by rocking shaft 30 which carries the segmental plates 29, and this 55 movement causes said bar to move downward and bear with considerable pressure on top of the pile of sheets a short distance to the rear of plate 14. The mechanism which actuates the drills 15 is now caused 60 to operate and as a result all of said drills are moved downward, thus forming a series of apertures through the pile of sheets positioned in the box or holder. After the 65 apertures have thus been formed, the drills 16 are elevated and the operator now swings

lever 18 to one side, as shown by dotted lines in Fig. 2, thus permitting the L-shaped portion of the assembling box to swing downward into the position shown by dotted lines in Fig. 1. The clamping bar 27 70 is now elevated by rocking shaft 30 which carries the clamping bar actuating members 29 and the perforated sheets can now be readily removed from the machine.

It will be readily understood that minor 75 changes in the size, form and construction of the various parts of my improved work holder for letter sheet perforating machines can be made and substituted for those herein shown and described, without departing 80 from the spirit of my invention, the scope of which is set forth in the appended claims.

What I claim is:

1. The combination with a perforating and binding machine table, of a member 85 hinged to the front edge of said table, which member is substantially L-shape in cross section, and a lever pivotally mounted on the underside of the table and adapted to engage beneath said hinged member to hold 90 the lower portion thereof in horizontal alignment with the table.

2. The combination with a perforating and binding machine table, of a work holder comprising a substantially L-shaped member, the free edge of the horizontal portion 95 of which is hinged to the edge of the work table.

3. The combination with a perforating and binding machine table, of a work holder 100 comprising a substantially L-shaped member, the free edge of the horizontal portion of which is hinged to the edge of the work table, and means on the underside of the 105 table for engaging the lower portion of the L-shaped member to hold said lower portion in horizontal alignment with said table.

4. The combination with a perforating and binding machine table, of a member 110 hinged to the front edge of said table, which member is substantially L-shape in cross section, a lever pivotally mounted on the underside of the table and adapted to engage beneath said hinged member to hold the 115 lower portion thereof in horizontal alignment with the table, and a pair of plates adjustable toward and away from each other upon the table, which plates constitute the side walls of the work holder.

5. The combination with a perforating 120 and binding machine table, of a work holder comprising a substantially L-shaped member, the free edge of the horizontal portion of which is hinged to the edge of the work table, and a pair of plates adjustable toward 125 and away from each other upon the table, which plates constitute the side walls of the work holder.

6. The combination with a perforating 130 and binding machine table, of a work holder

comprising a substantially L-shaped member, the free edge of the horizontal portion of which is hinged to the edge of the work table, means on the underside of the table 5 for engaging the lower portion of the L-shaped member to hold said lower portion in horizontal alinement with said table, and a pair of plates adjustable toward and away from each other upon the table, which

plates constitute the side walls of the work holder.

In testimony whereof I hereunto affix my signature in the presence of two witnesses, this 20th day of March, 1916.

WM. J. MORTON.
